UNITED STATES PATENT OFFICE.

HERMAN C. STOLLE, OF DAVENPORT, IOWA.

ELEVATOR AND HOLDER FOR RAILWAY SLEEPERS OR TIES.

1,389,393.

Specification of Letters Patent. Patented Aug. 30, 1921.

Application filed July 30, 1920. Serial No. 399,980.

To all whom it may concern:

Be it known that I, HERMAN C. STOLLE, a citizen of the United States, residing at Davenport, in the county of Scott and State 5 of Iowa, have invented new and useful Improvements in Elevators and Holders for Railway Sleepers or Ties, of which the following is a specification.

My present invention has for its object to 10 provide an efficient, labor saving sleeper or tie elevator and holder for use incident to the spiking of a railway rail to a sleeper or tie.

To the attainment of the foregoing the invention consists in the improvement as hereinafter described and definitely claimed.

In the accompanying drawings, hereby made a part hereof:—

Figure 1 is a view illustrating my novel elevator and holder as properly arranged relative to a sleeper or tie and a rail to be spiked to the sleeper or tie.

Figs. 2 and 3 are views making clear the construction of the holder *per se*.

Similar numerals of reference designate corresponding parts in all of the views of the drawings.

The sleeper or tie 1 and the rail 2 are of the ordinary well known constructions or 30 of any other constructions in connection with which my novel elevator and holder can be successfully operated.

Among other elements the elevator and holder includes a main frame of metal. The 35 said main frame has side bars 3 and spaced cross bars 4 and 5 interposed between and fixed with respect to the side bars 3. At their forward ends the side bars 3 are provided with seats 6, shaped by preference as 40 illustrated in order to receive and hold the base of a rail.

In addition to the main frame described, the elevator and holder comprises a drum shaft 7, journaled in the bars 4 and 5 and having a crank 8 at its rear or outer end, a cable 9, preferably of chain connected to and adapted to be wound on the drum shaft 7 and having a hook 10 whereby it may be readily looped and fastened about a sleeper 45 or tie as shown, a ratchet wheel 11 fixed on the outer portion of the drum shaft 7, and a dog or pawl 12 pivoted to the outer cross bar 4 and arranged to gravitationally cooperate with the ratchet wheel 11.

50 In the practical use of my novel elevator and holder the side bars of the main frame

are engaged with a rail as illustrated, and the cable 9 is connected to the sleeper or tie as shown. After the elevator and holder is applied as stated it will be observed that by 50 turning the drum shaft 7 a single operator is enabled to raise the sleeper or tie and to drive the spikes necessary to affix the rail to the sleeper or tie. It will also be manifest that through the medium of the means shown and 55 described the elevator and holder is enabled to raise the sleeper or tie with the expenditure of little effort. It will further be appreciated that my novel tie elevator and holder is adapted to be left in attached relation to 60 a rail while a train is passing without liability of being jarred loose, and that through the medium of my elevator and holder a tie 65 may be held against the rail until the rail is spiked to the tie. My novel elevator and 70 holder is also adapted to be used in close proximity to a building or wall, and is susceptible of being readily attached and detached.

The weight of the elevator and holder in 75 practice is about the same as that of a crow bar, and the elevator and holder embodies no delicate parts such as are likely to get out of order after a short period of use.

Having described my invention, what I 80 claim and desire to secure by Letters-Patent, is:—

1. A railway tie elevator and holder comprising a main frame having a portion adapted to rest a considerable distance above 90 a railway tie, and also having a portion shaped to receive and bearing against the bottom and one side of a rail base and against the opposite side of the rail web, and means carried by the elevated portion of 95 said frame and adapted to be connected to a tie whereby the tie may be raised and secured in raised position.

2. A railway tie elevator and holder comprising a main frame having a portion 100 adapted to rest a considerable distance above a railway tie, and also having a portion shaped to receive and bearing against the bottom and one side of a rail base and against the opposite side of the rail web, 105 a cable adapted to be connected with a tie, a drum journaled in the elevated portion of the main frame and adapted to be manually turning, said cable being connected to and adapted to be wound on said drum, and 110 means to prevent retrograde rotation of the drum.

3. A railway tie elevator and holder comprising a main frame having side bars the forward portions of which are shaped to receive and bear against the bottom and one side of a rail base and against the opposite side of a rail web and the rear portions of which are elevated, bars connecting the said side bars, a drum shaft journaled in said connecting bars and provided with a crank,

a ratchet wheel on the drum shaft, a dog or pawl on the outer cross bar and arranged to gravitationally coöperate with the ratchet wheel, and a cable connected to and adapted to be wound on the drum shaft, and also adapted to be connected to a tie. 10 15

In testimony whereof I affix my signature.

HERMAN C. STOLLE.
